DESIGN FOR A COMB CLEANER

Paul D. Humphries, Winter Haven, Fla.

Application January 25, 1945, Serial No. 117,592

Term of patent 14 years

(Cl. D9—2)

To all whom it may concern:

Be it known that I, Paul D. Humphries, a citizen of the United States, residing at the city of Winter Haven, in the county of Polk and State of Florida, have invented a new, original, and ornamental Design for a Comb Cleaner, of which the following is a specification, reference being had to the accompanying drawing, forming part thereof.

In the drawing

Fig. 1 is a top plan view of a comb cleaner showing my new design;

Fig. 2 is a side elevational view;

Fig. 3 is a bottom plan view; and

Fig. 4 is an end view, looking towards the left ends of the preceding figures.

I claim:

The ornamental design for a comb cleaner, as shown.

PAUL D. HUMPHRIES.
